US00D772201S

(12) **United States Design Patent** (10) **Patent No.:** **US D772,201 S**
(45) **Date of Patent:** **** Nov. 22, 2016**

(54) **CONTROL DEVICE**

(71) Applicant: **Kirk Lepchenske**, Pocatello (ID)

(72) Inventor: **Kirk Lepchenske**, Pocatello (ID)

(**) Term: **15 Years**

(21) Appl. No.: **29/533,282**

(22) Filed: **Jul. 15, 2015**

(51) LOC (10) Cl. **14-03**

(52) U.S. Cl.

USPC **D14/218**

(58) **Field of Classification Search**

USPC D14/218, 188, 225, 205, 155; D13/168; D21/566, 333; D10/104.1, 106.2;

CLAIM

The ornamental design for a control device, as shown and described.

DESCRIPTION

FIG. 1 is a top view for a control device, in accordance with the present invention;

FIG. 2 is a bottom view thereof;

FIG. 3 is a top perspective view thereof;

FIG. 4 is a bottom perspective thereof;

FIG. 5 is a left side view thereof;

FIG. 6 is a right side rear view thereof;

FIG. 7 is a front view thereof; and,

FIG. 8 is a rear view thereof.

The broken lines in the drawings are included for the purpose of illustrating environmental structure only and form no part of the claimed design.

1 Claim, 3 Drawing Sheets
